CLAIM

We claim the ornamental design for a thermostat, as shown and described.

DESCRIPTION

FIG. 1 is a front perspective view from above of the claimed design according to one embodiment;

FIG. 2 is a front side view of the claimed design of FIG. 1; FIG. 3 is a rear side view of the claimed design of FIG. 1; FIG. 4 is a right side view of the claimed design of FIG. 1; FIG. 5 is a left side view of the claimed design of FIG. 1; FIG. 6 is a top view of the claimed design of FIG. 1; and, FIG. 7 is a bottom view of the claimed design of FIG. 1. The broken lines in the drawings form no part of the claimed design. Lines having a jagged element show that no particular length of the portion is claimed, such lines and any portion of the article between such lines form no part of the claimed design. Oblique lines represent transparent or semi-transparent portions of the claimed design.
